United States Patent Office

Des. 208,022
Patented July 4, 1967

208,022

FOOTREST OR SIMILAR ARTICLE

David E. Ward, 7614 Wydown Blvd.,
Clayton, Mo. 63105

Filed Jan. 24, 1966, Ser. No. 725

Term of patent 14 years

(Cl. D15—8)

I claim:

The ornamental design for a footrest or similar article, as shown.
